MOSES HALL, JR., OF OSBORN, OHIO.

Letters Patent No. 72,290, dated December 17, 1867.

IMPROVED ASH-HOUSE.

The Schedule referred to in these Letters Patent and making part of the same.

TO ALL WHOM IT MAY CONCERN:

Be it known that I, MOSES HALL, Jr., of Osborn, in the county of Green, and State of Ohio, have invented a new and improved Ash-House; and I do hereby declare that the following is a full, clear, and exact description thereof, which will enable those skilled in the art to make and use the same, reference being had to the accompanying drawings, forming part of this specification.

This invention relates to a new and improved method of constructing ash-houses and leach-tub combined, whereby the same are rendered fire-proof, and by means of which ashes are more conveniently and economically separated from coals and dirt, and the same are more easily leached.

It consists of a hopper and screen upon a fire-proof ash-box, and the whole placed upon a leach-tub, said leach-tub being provided with a screen or perforated plate, through which the lye passes off. In the accompanying plate of drawings—

Figure 1 is a vertical sectional view of my invention, taken in the line *y y*, fig. 2.

Figure 2 is a vertical sectional view of the same, taken in the line *x x*, fig. 1.

Similar letters of reference indicate corresponding parts.

B is the hopper. C is the ash-box. D is the leach-tub. S is the screen between the hopper B and ash-box C. *h* are hooks, by which screen S is secured to sides of hopper B. *a* are the lids. A is the frame of the box C. *e* is the planking forming sides of same. *f* is a metallic lining covering inside of box C. *A'* are handles, by means of which box C is lifted from leach-tub D. *a'* are hooks, by means of which frame A is secured to frame G. G is the frame of the leach-tub D. K K is the top of same, separating box C from leach-tub D. S' is a raised screen or raised perforated plate upon the top or separator K K. *o* is an orifice or pipe, through which the lye passes off. The hopper B is composed of two sides without ends, said sides being of sufficient height and of sufficient distance apart to contain the required quantity of coals and ashes. Said sides are provided upon their upper edges with lids secured to the sides by hinges, so as that said lids will fold towards each other, meeting in the centre between the said sides; and said lids are slightly inclined to each, so as when closed to form a kind of roof.

The ash-box C is formed of a frame, A, in the shape of a truncated pyramid, said frame A being covered on the inside, except at the top, where it opens into the hopper, and except at the bottom, with a suitable planking, *e*, so as to form a box, and said planking *e* is covered with a metallic lining, *f*, on the inside, by means of which the said box C is rendered fire-proof. One side of the frame A is higher than the other, so as that the screen S is sufficiently inclined, so as that the coals and dirt, when separated from the ashes, may be conveniently deposited outside the ash-house, in some receptacle for the same. Said box C is provided with suitable handles, *A'*, by means of which it may be removed from the leach-tub D, when necessary to clean the ashes from said box C. The said box C conforms to the shape of the frame A, and is larger at the bottom, so that ashes contained in said box C will readily drop or fall out when said box C is removed from the leach-tub D. The lower parts of the frame A are bevelled off, as shown in the drawing, so as to fit into corresponding bevelled parts on the upper part of the frame G. Upon the frame A are suitable hooks, *a'*, as shown by dotted lines in the drawing, which, engaging in staples in the frame G, hold the ash-box C securely upon the leach-tub D, and so that said box C may at any time be easily removed.

The leach-tub D consists of a frame, G, and a top, K K, composed of two parts, K, inclining downwards to each other, and meeting in the centre of the leach-tub D, as shown in the drawing, fig. 1, the parts K being also covered with a metallic lining, so as to render said leach-tub D fire-proof. Upon the said parts K, and extending from one to the other, as shown, is a raised or curved screen or perforated plate, S', so as to form a chamber between said screen S' and the parts K. In said chamber is an orifice or pipe, *o*, by means of which the lye is drawn off. The object of said screen S' is to separate the ashes from the lye, and is a better means of accomplishing such purpose than the straw or other materials now in common use. The parts K form the bottom of the ash-house, as shown in the drawing.

The operation is readily seen from the drawing. Ashes being sifted from the coal and dirt in the hopper B by the screen S, are deposited in the box C upon the parts K K and screen S'. The screen S may then be

removed, and water poured upon the ashes in box C, which said water will leach through the ashes in said box, making lye, which, passing through the screen S', is drawn off at the orifice or pipe o.

Constructed as above described, it forms a convenient and fire-proof ash-house and leach-tub combined.

I claim as new, and desire to secure by Letters Patent—

1. A fire-proof ash-house and leach-tub combined, substantially as shown and described, and for the purposes set forth.

2. The fire-proof box A, in combination with the hopper B and screen C, substantially as shown and described, and for the purpose set forth.

3. The fire-proof leach-tub D, in combination with the parts K and screen S', substantially as shown and described, and for the purposes set forth.

4. A fire-proof box C, in combination with the fire-proof leach-tub D, substantially as shown and described, and for the purposes set forth.

The above specification of my invention signed by me, this sixteenth day of October, A. D. 1867.
